UNITED STATES PATENT OFFICE

129,825

DESIGN FOR A BOOKCASE

Irene Simon, Pittsburgh, Pa.

Application July 31, 1941, Serial No. 102,609

Term of patent 7 years

To all whom it may concern:

Be it known that I, Irene Simon, a citizen of the United States, residing at Pittsburgh, in the county of Allegheny, State of Pennsylvania, have invented a new, original, and ornamental Design for a Bookcase, of which the following is a specification, reference being had to the accompanying drawing, forming a part thereof.

The figure is a perspective view of a bookcase embodying my new design.

I claim:

The ornamental design for a bookcase, as shown.

IRENE SIMON.
